US00D890107S

(12) **United States Design Patent** (10) **Patent No.:** **US D890,107 S**
(45) **Date of Patent:** **** Jul. 14, 2020**

(54) **TRANSMITTER PARTS**

(71) Applicant: **The Chamberlain Group, Inc.**, Oak Brook, IL (US)

(72) Inventor: **Mark Edward Miller**, Woodridge, IL (US)

(73) Assignee: **The Chamberlain Group, Inc.**, Oak Brook, IL (US)

(**) Term: **15 Years**

(21) Appl. No.: **29/669,496**

(22) Filed: **Nov. 8, 2018**

Related U.S. Application Data

(62) Division of application No. 29/621,185, filed on Oct. 5, 2017, now Pat. No. Des. 836,568, which is a division of application No. 29/573,747, filed on Aug. 9, 2016, now Pat. No. Des. 806,043.

CLAIM

I claim the ornamental design for transmitter parts, as shown and described.

DESCRIPTION

FIG. 1 is a perspective view of transmitter parts in accordance with my new design;

FIG. 2 is a front elevation view of the transmitter parts of FIG. 1;

FIG. 3 is a rear elevation view of the transmitter parts of FIGS. 1-2;

FIG. 4 is a left side elevation view of the transmitter parts of FIGS. 1-3;

FIG. 5 is a right side elevation view of the transmitter parts of FIGS. 1-4;

FIG. 6 is a top view of the transmitter parts of FIGS. 1-5; and,

FIG. 7 is a bottom view of the transmitter parts of FIGS. 1-6. The transmitter portions shown in broken lines in the figures depict unclaimed environmental subject matter, are for illustrative purposes only, and form no part of the claimed design.

1 Claim, 5 Drawing Sheets
